Patented May 2, 1922.

Inventor

Starr M. Gibbs

UNITED STATES PATENT OFFICE.

STARR M. GIBBS, OF MOUNT RAINIER, MARYLAND.

HAND VISE.

1,414,354.

Specification of Letters Patent. Patented May 2, 1922.

Application filed September 6, 1921. Serial No. 498,620.

To all whom it may concern:

Be it known that I, STARR M. GIBBS, a citizen of the United States, residing at Mount Rainier, in Prince Georges County 5 and State of Maryland, have invented new and useful Improvements in Hand Vises, of which the following is a specification.

This invention relates to certain improvements in gripping tools of that class having crossed levers and jaws so correlated that the jaws move in nearly parallel planes when being open or closed and the jaws of the vise are parallel when the jaws are adjusted, with a sufficient grip to hold flat or 15 round articles firmly between the jaws. The jaws of this vise will also shape themselves to a slightly tapered article when under sufficient pressure of the screw and will hold fast and firm enough for all ordinary work.

This hand vise when closed on to flat or round articles first comes in contact at the nose or end of jaws and then as pressure is applied with the screw the jaws 25 straighten out parallel with each other shaping them to the article in the jaws, thereby creating a pressure so great that the article held is as fast and firm as though it were a part of the vise. Another advantage that I claim is that because of the 30 great strength of this vise the jaws can be made smooth and will not scratch or mark up gold or silver or similar metals, the vise being especially adapted to the jeweler, 35 tool maker, and machinist.

Hand vises form a leading type of hand tools of the class herein referred to and such hand vises have been selected to exemplify the present improvements but it 40 should be understood that it is my purpose to embody the present improvements in such hand tools generally as lend themselves to the utilization of the features hereinafter set forth, and hence reserve the liberty of embodying the improvements hereinafter described and claimed in hand tools other than those known specifically as hand vises and to all such tools in which said features may be usefully employed.

One of the important objects of the present invention is to provide a tool of the class herein set forth which will be of strong durable neat and well balanced construction and which may be most readily 55 and conveniently adjusted to fit different sizes of articles.

The foregoing objects of the invention and others which will appear from the following description and accompanying drawings disclosing the preferred embodiment thereof are best secured from the constructions illustrated in the accompanying drawings, wherein—Figure 1. is an elevation of a vise embodying the invention showing the parts in both open and closed position. Fig. 60 1: vise jaws engage work W. first at nose of jaws N. leaving a clearance or open space at jaws C. which is taken up and the jaws are parallel when under necessary sufficient pressure of the screw. Thereby adding 65 to the gripping power of the jaws.

Fig. 2 is an elevation showing a bisection view bringing out clearly all the working points.

Fig. 3 is a longitudinal elevation on a 75 plane at right angles to that from which the device is viewed in Figs. 1 and 2 showing the top of the vise.

Fig. 4 is a longitudinal elevation showing the bottom of the vise an opposite view of 80 Fig. 3.

Figs. 1 and 2 show that the body 1 and jaws 2 are integral and 2' and 3 are likewise open at the same time and parallel.

The tool of the present invention includes 85 two bar members having jaws 2 and 3 fixedly connected to one end thereof; two or more pairs of crossed levers 5 and 5' whose forward ends are pivoted to body of vise at 6 and 6' and whose rear ends are 90 pivoted to body or handle at 7 and 7'. The said levers being also pivoted to each other at their place of intersection and serving to keep the parts in parallelism with each other while the tool is being adjusted; in bar 95 1 at 16 and bar 2' at 16' a tapered cut out is provided for lever 5' to close in when the vise is in closed position. And an adjusting screw 4 which is arranged just rearward of the jaws 2 and 3 and goes through hole of 100 bar 1 at rear of jaw 2 into a threaded hole of bar 2' at rear of jaw 3. Said screw having an annular shoulder 11 which is held in a retainer 12 which is fastened to body member 1 at 14 in such a way that when the 105 screw is rotated the jaws open or close according to the way that the screw is turned.

Like characters of reference denote like parts in the several views. The adjusting screw 4 also having a cap screw 4' which is 110 a safety device preventing the annular shoulder retainer screw 14 from breaking when

the jaws are open to their full capacity. The screw 4 has lever handle 15 which makes it possible to screw the jaws tight enough to hold work within the jaws. In the particular form of the device herein exemplified the jaw 2 body section 1 are integral with each other, and the jaw 3 body section 2' are also integral with each other. The lever 5 is pivoted at its forward end at the place 10 marked 6 to the body 1 and has its rear end provided with a guide pin or projection 7 which traverses a slot 10 formed in the rear end of the body section 2'. Another lever 5' is pivoted at its forward end at the place 15 marked 6 to the body 2' and has its rear end provided with a guide pin or projection 7 which traverses a slot 10 in the rear end of body section 1. These two levers are pivoted to each other at their place of intersection 8 20 midway the length of the levers and in a plane longitudinally between the confronting surfaces of the body numbers 1 and 2'. Preferably there are two pairs of crossed levers employed one pair at each side of the 25 vise as shown in Figs. 3 and 4.

While particular devices constituting shoulder screws and nuts 7 have been disclosed any means or correlation of parts which will act as pivots or rivets to pin levers to vise will be within the spirit and scope of the claim. From the foregoing the construction operation and advantages of the present invention will be readily understood, and it will be apparent that changes 30 in the form, construction and relative arrangement of the parts may be made with-

out departing from the spirit of the invention or the scope of the subjoined claim.

It will be understood that the part named in the foregoing description and following 40 claim as the body section is intended arbitrarily to include that part of the device which is back of the screw 4. 1 and 2' which also serves as a handle.

Having now described the invention what 45 I believe to be new, and desire to secure by Letters Patent, is:

A hand vise comprising jaws, each jaw including a jaw proper and a body section, an adjusting screw provided with an annular shoulder facing one of the jaws, cross levers pivoted to each other at their place of intersection and having one pair of ends pivoted to said body sections contiguous to the 50 said adjusting screw and the other pair of ends pivoted in slots in the opposite ends of the said body sections, a retaining device fastened to one of the body sections, one end of which fits over the annular shoulder of the adjusting screw to make the top jaw of 55 the vise follow the annular shoulder of the adjusting screw as the adjusting screw is rotated to open the jaws, a lever handle mounted on said adjusting screw for operating the same, a cap screw on the opposite 60 end of the adjusting screw serving as a safety device to prevent the breaking of the annular shoulder retaining device.

In testimony whereof I have hereunto set 65 my hand.

STARR M. GIBBS.
